Design No. 12,013, dated November 2, 1880.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of **Design No. 12,013**, dated **November 2, 1880.**

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of figures hereinafter more fully described.

The accompanying photograph illustrates a face view of wall-paper having my new design.

15 Two parallel stripes, A and B, each one ornamented with alternate vertical and horizontal bars, and a single vertical bar of nearly the width of the stripe separating three parallel bars, which run at right angles thereto, appear on each side of the main design. Between these stripes A and B runs a vine or branch, C' C² C³, in an S-shaped curve, the portion C³ showing the beginning of such a vine, C' its continuation, and C² its ending.

From the vine C' C² C³ appear to grow large 25 flowers D D D, having inner bead-like clusters, and smaller star-flowers E E E, and also leaves, some notched, as G G, and others smooth and tapering, as H H. The effect is that of a vine or branch curving between two 30 parallel stripes, and bearing on it numerous flowers and leaves of the style indicated.

I claim—

1. The design for wall-paper, consisting of the vine C' C² C³, with its flowers D and E 35 and leaves G and H, substantially as shown.
2. The design for wall-paper, consisting of the stripe A, with its ornamentation of alternate vertical and horizontal bars, substantially as shown.
3. The design for wall-paper, consisting of the vine C' C² C³, with the flowers D and E and leaves G and H, and of the stripes A and B, substantially as shown.

EDUARD LEISSNER.
